(57) **CLAIM**

The ornamental design for an electronic cigarette charger, as shown and described.

DESCRIPTION

FIG. 1 is a top, front and right side perspective view of an electronic cigarette charger showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is an enlarged view of portion 8 in FIG. 1.

The broken lines in the drawings depict portions of the electronic cigarette charger that form no part of the claimed design.
